JOSEPH C. COULOMBE, OF LOWELL, MASSACHUSETTS.

VACUUM FUEL-FEED DEVICE.

1,421,067.

Specification of Letters Patent. Patented June 27, 1922.

Application filed October 27, 1915. Serial No. 58,253.

To all whom it may concern:

Be it known that I, JOSEPH C. COULOMBE, a citizen of the United States, and a resident of Lowell, in the county of Middlesex and State of Massachusetts, have invented certain new and useful Improvements in Vacuum Fuel-Feed Devices, of which the following is a specification.

The invention relates to liquid feeding devices and is more particularly adapted for raising a liquid from a comparatively low level to a high level, and distributing said liquid from the high level to apparatus in which it may be used. It is designed more especially to be operated under reduced atmospheric pressure produced in any desired manner, as for instance, by the piston of an engine of a liquid hydrocarbon type.

The main object of the invention is to produce a simple, effective apparatus which will be entirely automatic in its action and which will, without the use of complex valve systems, control the suction effect with reference to the fluid to be raised and distributed.

A further object is to provide a combination float and valve which, acting under its buoyancy and in conjunction with controlled sub-atmospheric pressures, automatically control the flow of a fluid.

A further object is to provide a device having a suction chamber, a float chamber and a delivery chamber so combined and associated that a single float and attached valve will directly control the degree of suction in the suction chamber, the flow of liquid to said chamber and the disposal of the liquid to the distributing chamber.

The present invention is analogous to, but an improvement upon the device of a pending application, Se. No. 32,927, filed June 8, 1915, entitled Fuel feeding and carbureting mechanism.

In said application there is described a device in which the float controls the atmospheric air valve which intermittently opens and closes for providing a closed suction chamber or breaking the vacuum in said chamber, thus controlling the flow of fluid into the suction chamber and from the suction chamber to the distributing chamber. In this prior device a number of valves were required, and the suction was produced by

connecting the suction chamber with the manifold of a gas engine. 55

The present device contemplates connection of its suction chamber directly with one of the cylinders of a gas engine and has marked advantages as I hereinafter set forth. 60

Furthermore, its float controls the passage between the suction chamber and the distributing chamber, thus doing away with some of the disadvantages of various valves of the prior application. 65

Referring to the drawings:

Fig. 1 is a diagrammatic view illustrating a possible disposition of the parts upon an automobile.

Fig. 2 is a similar view in fragmentary form illustrating a device as it might be applied to the manifold of an engine.

Fig. 3 is a detail sectional view of a check-valve and pet-cock of the engine to which the device is applied. 75

Fig. 4 is a reduced plan view of the apparatus.

Fig. 5 is a vertical section through the device.

I referred herein to a pending application 80 in which the vacuum feeding device was attached directly to the manifold of the engine. This method of attachment has certain disadvantages. When a car is running on a stiff grade with the throttle wide 85 open, it not infrequently happens that the feed device and carbureter are drained, owing to the fact that there is comparatively little suction in the manifold. In fact, there are many instances in which such a condition may occur. Obviously, the manifold is opened through the carbureter, and the degree of vacuum depends entirely upon the suction in the manifold which connects the various cylinders. 90

In the present device, an arrangement is shown for connecting the vacuum chamber directly with one of the cylinders so that the full force and effect of the suction strokes of the piston are made available 100 for the vacuum chamber of the device. Although this produces an intermittent suction available only upon the suction stroke of the engine, the controlling valve and mechanism of the feed device is so arranged 105 that a perfect feed of fuel can be secured.

There is no failure of the device to draw up the liquid into the vacuum chamber and there are no atmospheric valves and delicate parts which might become disturbed and inoperative under the rough usage imposed upon such a structure when used upon a vibrating automobile or other device.

The distributing chamber is constantly under atmospheric pressure through an open atmospheric connection and there is a valve controlling the single passage connecting the distributing chamber and the suction chamber, which valve is operated by a float in the suction chamber. This valve serves to control the flow of liquid from the suction chamber to the distributing chamber and serves the further function of equalizing the relative pressures existing in the distributing chamber, which is open to atmosphere, and the suction chamber, which is constantly under the action of suction and has a reduced atmospheric pressure. The opening of the valve increases the pressure in the suction chamber to an extent sufficient to permit the contents thereof to flow by gravity into the distributing chamber.

Of course, it is not impossible to utilize the present structure with a connection to the manifold as was done in the prior application referred to, but it is quite possible and preferable to make the connections directly with the cylinder.

In the accompanying drawings, the numeral 1, denotes a cylindrical casing which is divided into a suction chamber A, and a distributing chamber B, by a partition 2. The structural form of this casing may be of any desired material and type. No attempt has been made in the drawings to illustrate a finished form of casing such as was shown in my prior application.

The distributing chamber B, is connected through a hollow bolt 3, with the atmosphere through ports 4, which communicate with a splash pot 5, having openings 6, at or near its top.

As illustrated, the bolt 3, is screwed into a nipple in the partition 2, and has a shoulder 7, which engages the bottom flange 8, of the splash pot. Its upper end is plugged with a screw 9. This arrangement prevents any possible splashing of liquid from the atmospheric opening 6, inasmuch as the splash pot 5, will temporarily hold any liquid thrown through the ports 4, said liquid dripping back through the ports into the chamber B.

Concentrically arranged within the chamber A, is a downwardly extending tube 10, which provides a float chamber C. This chamber C, is closed at its top and the lower end is closed and opened by the fluid which forms a liquid seal.

Centrally arranged in the partition 2, is a valve opening 11, having a valve seat 12,

upon which rests a disk valve of suitable character 13.

This valve 13, is controlled by a float D, and has a stem 14, extending through the guide 15, in the center of the float. The guide 15, has shoulders which form a stop against which the head 16, of the valve stem 14, will impinge when the float rises.

A centrally located tube 17, extends upwardly from the float and encircles a guide 75 and bearing pin 18, which projects downwardly from the upper end of the casing.

A spring 19, is arranged at the underside of the guide 15, and over the disk of the valve. This gives a resilient connection between the valve and the float and prevents unseating of the valve when the parts are under vibration.

The float D, extends upwardly into the lower end of the chamber C, and is provided on its lower side with a baffle-plate 20, which projects beyond the walls of the chamber C, and thereby prevents the entrance of air bubbles to said chamber. The baffle-plate 85 diverts the bubbles which pass up into the 90 chamber A.

The upper end of the casing is provided with a nipple 21, within which is arranged a valve seat 22, and a suitable check-valve 23. In the form illustrated, a ball-valve is 95 employed which is prevented from undue rise by a pin 24.

The nipple 21, though a conduit or pipe 25 is connected with the engine cylinder, and a nipple 26, through a conduit or pipe 27, 100 forms communication between the suction chamber A, and the fuel supply tank E. The lower distributing chamber B, through a nipple 28, and connecting conduit or pipe 29, connects the distributing chamber B, 105 with the carburetting device F.

In Fig. 2 a detail sectional form of carbureter F', is illustrated with an overflow connection to the fuel tank E, to provide a constant level for the fuel chamber of the 110 carbureter.

The valve 23, acts as a check-valve for the vacuum chamber A, and heavy duty upon this valve is very much reduced by a special check-valve at the engine head which controls the pipe 25.

In place of the ordinary pet-cock, a special form of T connection 30, is employed in the cylinder head 31, and the pet-cock 32 is screwed into the upper end of the T.

Extending into the T is a flanged nipple 33, which is held in place by a union nut 34, which also gives a tight connection for the end 35, of the pipe 25.

The inner end of the flanged nipple 33, 125 provides a valve seat 36, for the valve 37. Encircling the nipple 33, is a valve cage 38, which has a perforation 39, which provides a suction port and a perforation 40, which serve to effectively unseat the valve 37, upon 130

each suction stroke of the piston. Upon the suction stroke, the valve 37, is withdrawn from its seat upon the first movement of the piston, and full suction is produced in the 5 pipe 25, during the whole stroke. Immediately upon the return stroke of the piston, the valve 37, is set back upon its seat. In the meantime, the check-valve 23, maintains the reduced atmospheric condition in the suction 10 chamber A.

This suction is sufficient to draw up liquid from the tank E, through the pipe 27, of the suction chamber A. As the liquid rises in the chamber A, it forms a liquid seal between 15 said chamber and the float chamber C. During its rise, the float will rise until the head 16, of the valve stem 14, is engaged by the stop 15 carried by the float, which slightly raises the valve 13, from its seat 12.

20 Thereupon, air entering through the atmospheric opening 6, will bubble up through the liquid in the chamber A, partially reducing the vacuum in said chamber.

When a sufficient quantity of liquid has 25 been drawn into the chamber A, the float will rise still higher but, of course, the rise and level of the liquid within the chamber C, will not be as rapid as it is in the chamber A. As soon as the level of the liquid in the 30 chambers A and C, has risen sufficiently to raise the float D, to fully open the valve 13, the contents of the chamber A, will drop into the distributing chamber B, due to the inrush of air through the now opened valve 35 13—said air bubbling up through the liquid of the chamber A.

As soon as the suction in the chamber A, is sufficiently reduced, the liquid of said chamber will fall by gravity into the chamber B, and as soon as its level is below the bottom of the casing 10, of the chamber C, the liquid seal of said chamber is broken and the float will drop, closing the port 13. This operation of filling and feeding is, of 45 course, very rapid and maintains a substantially constant volume of liquid in the distributing chamber B.

Where the device is used with a constant level carburetting device such as described 50 in my prior application above referred to and such as illustrated in Fig. 2, any overflow from the carbureter will be carried back into the main fuel tank E.

In Fig. 2, the casing 1, is illustrated as 55 mounted above the carbureter F', and has its suction pipe 25, connecting with the manifold 25^a. Its fuel pipe 27, is connected with the tank E, and the distributing pipe 29, communicates with the carbureter F', which 60 is provided with an overflow duct 29^a, communicating with the main tank E.

It will be seen from the above that the device is even more simple than that of the prior application referred to and has no 65 specially controlled atmospheric port. It

has a single valve controlling the main port between the suction chamber and distributing chamber. This single valve controls the flow of fluid from the suction chamber to the distributing chamber and controls 70 the equalization of pressures between said chambers as it is actuated by the float.

Thus, the controlling valve may be of comparatively large and substantial character and operates more certainly than the 75 delicate atmospheric air valves heretofore contemplated. This is due to the float and inverted chamber which will control the valve which passes the liquid to the distributing chamber and permits the passage of 80 air to the suction chamber by which the evolution of breaking suction and passing liquid under gravity is evolved.

Of course, the exact details of construction and the exact form of the valves may be 85 modified and designed to meet the exigencies of any particular demand, and the device may be utilized for the purpose of feeding any liquid. It need not of necessity be confined to a fuel system of an automobile. 90 It may be utilized wherever it is desirable to have a feeding device operated by suction or vacuum at a point higher than the supply of liquid and the device to which the liquid is to be distributed. 95

What I claim as my invention and desire to secure by Letters Patent is:

1. In a liquid feeding device, in combination a suction chamber, a distributing chamber, said suction chamber closed except for the connection with a source of suction and a source of liquid supply, said distributing chamber being always under atmospheric pressure, a valve opening between the two chambers, a valve controlling said valve opening, and a float controlling said valve dependent upon the rise and fall of level of fluid in the suction chamber, said valve controlling the flow of liquid from the suction chamber to the distributing chamber and controlling the reduction of suction in the suction chamber to permit said flow under gravity. 105

2. A liquid feeding device having a suction chamber constantly under sub-atmospheric pressure and a distributing chamber constantly under atmospheric pressure arranged to receive the contents of the suction chamber by gravity, connections for causing a suction within said suction chamber, a fluid supply connection through which said chamber receives liquid under the action of the suction, a normally open atmospheric opening to the distributing chamber, a valve opening between the suction and distributing chambers, a single valve controlling said opening, and a float controlling the said valve and dependent for its operation upon the level of the liquid in the suction chamber, said single valve permitting a rise of 110 120 125 130

pressure in the suction chamber and a flow of fluid from the suction chamber to the distributing chamber.

3. In a device of the character described, 5 a suction chamber, a distributing chamber, a float controlling chamber arranged within the suction chamber, a float extending into said chamber, a valve opening intermediate the suction chamber and distributing chamber, 10 a normally open atmospheric connection for the distributing chamber, a valve controlling the valve opening between the suction and distributing chambers and controlling the passage of atmospheric air from 15 the distributing chamber to the suction chamber and controlling the flow of liquid between said chambers, a float arranged within the float chamber connected with and controlling said valve, said float dependent 20 for its action upon the level of liquid in the suction chamber and the float chamber, and the lowering of the level of liquid of the suction chamber below the float chamber.

4. In a device of the character described, 25 a suction chamber, means for producing suction in said chamber, a distributing chamber open to atmospheric pressure, a valve opening intermediate the two chambers, a float chamber arranged in the suction chamber and closed except for its opening at its lower end into the suction chamber, a float extending into said float chamber, a valve normally covering the valve opening between the suction and distributing chambers 30 and connected with and controlled by the float, said valve and float adapted to rise and reduce the degree of suction in the suction chamber during a rise of the level of the liquid in said chamber and adapted 35 to permit the flow under gravity, of the contents of said chamber to the distributing chamber while the level of the liquid in said suction chamber is above the lower end of the float chamber whereby said float 40 while buoyant in the liquid of the float chamber permits admission of air to the suction chamber for a predetermined period and closes its controlled valve upon a lowering of the liquid below the bottom of the 45 float chamber.

5. In a device of the character described, 50 a suction chamber closed except for a suction connection, a liquid supply connection, and a valve controlled connection with a distributing chamber hereinafter specified, means for producing suction, a liquid supply located below the suction chamber, a distributing chamber open to atmospheric pressure, a valve opening between the distributing chamber and suction chamber, a normally closed valve controlling said connection, a float controlling said valve, said valve and float controlled by the level of liquid within the suction chamber and controlling the flow of liquid from said suction

chamber to the distributing chamber under gravity and controlling the reduction of suction in the suction chamber, whereby the relative pressures between the suction chamber and distributing chamber are sufficiently 70 equalized to permit a flow of the fluid of the suction chamber to the distributing chamber.

6. In a device of the character described, 75 a suction chamber and a distributing chamber, the former connected with a source of suction and with a source of liquid supply, the latter normally opened to the atmosphere, a float in the suction chamber controlled by the level of the liquid therein, a 80 valve opening between the suction and distributing chambers, a valve controlling said opening and controlled by said float, said valve controlling the flow of liquid from the suction chamber to the distributing chamber and also controlling the flow of 85 atmospheric air from the distributing chamber to the suction chamber whereby the suction of said suction chamber and the level of liquid therein is automatically controlled. 90

7. In a device of the character described, 95 a suction chamber and a distributing chamber, a valve controlled passage between said chambers, a valve controlling said passage, a suction connection and a liquid supply connection for the suction chamber, an atmospheric connection normally open for the distributing chamber, and a float combined with and governing the valve, said valve forming the sole means of controlling the 100 flow of fluid from the suction to the distributing chamber and the admission of atmospheric pressures to the suction chamber as it is moved by the float upon rise and fall of level of liquid in the suction chamber. 105

8. In a device of the character described, 110 having a suction chamber connected with a suction device and with a source of liquid supply, a single valve controlling the flow of liquid from said chamber, and the introduction of atmospheric air thereto, a float controlling chamber arranged in the suction chamber, and means including a float and the float chamber for controlling said valve upon variations in the level of the 115 liquid of the suction chamber and the degree of vacuum in the suction chamber.

9. In a fuel feeding device for gas engines arranged above a source of supply and adapted to receive liquid by suction and distribute said liquid by gravity to a carbureter, in combination, a suction chamber, a float in said chamber, and a valve actuated by the float and controlling the gravitational flow of liquid from the suction chamber, 120 a liquid supply connection for the suction chamber, a suction connection therefor, a connection therefrom to a cylinder of a gas engine, a check valve arranged in the suction connection of the suction chamber, a 125 130

check valve arranged in the connection at the cylinder of the engine, said check valves co-operating to maintain partial vacuum in the suction chamber, and a connection from

5 the feeding device to the carbureter of the engine.

10. A liquid feeding device arranged above a source of liquid supply and adapted to feed liquid by gravity, said device having a suction chamber, and means for controlling distribution of liquid drawn into the suction chamber, a direct connection from the suction chamber to the suction device, and means in said connection for preventing back pressure from the suction device entering the suction chamber, said means comprising a check valve in the connection at the suction device and a check valve in the connection at the suction chamber.

20. 11. A liquid feeding device arranged above a source of liquid supply and having a suction chamber, an interior float chamber closed except as to its bottom and adapted to be closed and sealed by the liquid in the suction chamber, a float in said float chamber, a distributing chamber controlled as to its source of supply by the float of the float chamber, a direct connection between the suction chamber and a source of suction, and a check valve device in said connection at its point of juncture with the source of suction for preventing back pressure in said connection, and a check valve in the connection at its entrance to the suction chamber to prevent back pressure from the suction device to the suction chamber.

25. 12. A liquid feeding device arranged above a source of liquid supply and having a suction chamber, a float chamber arranged in the suction chamber and closed except as to its bottom, said chamber adapted to be closed and sealed by the liquid in the suction chamber, a float in said float chamber, a valve controlled by said float, said valve controlling the degree of suction in the suction chamber and the flow of liquid therefrom, a distributing chamber controlled as to its source of supply by the valve and float

30. of the float chamber, a direct suction connection between the suction chamber and a suction device, and a valve at each end of said connection, said valves opened only upon suction produced in the suction device.

35. 13. A liquid feeding device consisting of a suction chamber, a distributing chamber to which liquid is fed from the suction chamber by gravity, a control chamber within the said suction chamber, means for producing a suction in said suction chamber, float operated means including a valve for sufficiently equalizing the relative pressures of the suction chamber and distributing chamber to permit the liquid of said suction chamber to flow by gravity to the distrib-

uting chamber, and a float influenced in its action by said control chamber for periodically operating the valve and float operating means.

14. A liquid feeding device consisting of a suction chamber, means for producing suction in said chamber, a distributing chamber constantly under atmospheric pressure adapted to receive the liquid of the suction chamber, a control chamber within said suction chamber, float operated means for sufficiently equalizing the relative pressures of the suction chamber and distributing chamber to permit a flow of liquid from the suction chamber to the distributing chamber by gravity, and a float arranged in the control chamber and connected with the float operated means.

15. In a fuel feeding device for engines in combination with a supply tank located at a low level and a carbureter arranged at a higher level, a fuel receptacle arranged at a level higher than the supply tank and carbureter and formed with a suction chamber and a distributing chamber, a connection from the suction chamber of the fuel receptacle to the supply tank, a connection from the distributing chamber of the fuel receptacle to the carbureter, for delivering liquid by gravity thereto, a connection from the suction chamber to the engine cylinder for producing sub-atmospheric condition or suction for the suction chamber at all times during the operation of the engine, an air inlet for periodically breaking the suction in the suction chamber, a valve controlling said air inlet, said valve having a comparatively large area and controlling the gravitational flow of fuel from the suction chamber, and a float actuating said valve, to break the vacuum of the suction chamber, or close said chamber for the establishing of a vacuum effect therein dependent upon the rise and fall of the level of fuel in the fuel tank, and controlling the passage of said fuel from the suction chamber.

16. In a liquid feeding device in combination with a main liquid supply tank at a low level, a liquid supply receptacle located above said tank, said receptacle closed except as to the connections hereinafter set forth, viz, a connection from the liquid supply receptacle to the main tank, an exhaust connection for the supply receptacle for producing sub-atmospheric conditions therein, and an opening through the bottom of the receptacle, a chamber connected with the supply receptacle to receive and distribute by gravity liquid discharged from the supply receptacle through the opening last mentioned, an atmospheric inlet connected with the distributing chamber, a valve controlling the communication of the receptacle with the distributing chamber, a float device in said receptacle, an operative

120
125
130

connection therefrom to the valve for opening and closing the latter according to the height of liquid in the receptacle.

17. In combination with a supply tank located at a low level, a liquid supply receptacle located at a level above said tank, a liquid supply connection from the tank to the receptacle, a suction connection for the receptacle for producing a sub-atmospheric pressure therein and a connection with a distributing chamber through which liquid is discharged from the supply receptacle, said liquid supply receptacle being closed except for said connections, and a valve controlled connection between said receptacle and a supplemental distributing chamber, a supplemental distributing chamber for receiving the liquid discharged from the supply receptacle by gravity, an atmospheric connection opening to the upper portion of the supplemental chamber, a valve controlling the communication of the liquid supply receptacle with the distributing chamber, a device in the receptacle operated by the rise and fall of level of liquid therein, operative connections from said device to the valve for positively opening and closing the valve, said valve and the passage controlled thereby and connecting the liquid supply receptacle and distributing chamber being substantially large to permit rapid discharge of the liquid of the fuel receptacle and permitting the passage of air into the liquid supply receptacle during the flow of liquid from said receptacle to the distributing chamber.
18. In combination with a main low level liquid supply tank, a liquid supply receptacle located at a level higher than said tank and closed except for a fuel connection, a suction connection, and a discharge connection, said discharge connection being open to atmospheric pressure, a suction connection for reducing the pressure in the higher liquid supply chamber below that of atmosphere, a connection from said receptacle to the main fuel supply tank, an atmospheric connection extending to the discharge connection of the supply chamber, a valve controlling the admission of atmos-

phere to the supply chamber and the flow of liquid from said chamber, and means within the chamber actuated by the rise and fall of liquid therein for opening and closing said valve.

19. In combination with a main low level liquid supply tank, a liquid supply receptacle located in a plane above said tank and closed except as to the connections hereinafter indicated; a supplemental chamber connected with said receptacle for discharge of liquid by gravity from said receptacle into said supplemental chamber; a supply connection from the main tank to said receptacle, and an exhaust connection to said receptacle for reducing the pressure therein below that of the atmosphere; an atmosphere inlet connection to the upper part of said supplemental chamber; a valve controlling the communication of said receptacle with said supplemental chamber, and means in said receptacle for opening and closing said valve at pre-determined high and low levels of the liquid in said receptacle.

20. In combination with a main low level liquid supply tank, a liquid supply receptacle located in a plane above said tank and closed except as to connections hereinafter mentioned; a liquid supply connection from said tank to said receptacle; a supplemental chamber, connections from said receptacle to said supplemental chamber for discharge of liquid by gravity from the receptacle into the chamber; an exhaust connection to said receptacle for reducing the pressure therein below that of the atmosphere; an atmosphere inlet connection to the upper part of said supplemental chamber; a valve which controls the discharge of liquid from the receptacle to the supplemental chamber; a float device in said receptacle and operating connections therefrom to the valve for opening and closing the latter according to the height of liquid in the receptacle.

JOSEPH C. COULOMBE.
